UNITED STATES PATENT OFFICE

EDGAR E. GREVE, OF BELLEVUE, PENNSYLVANIA, ASSIGNOR, BY MESNE ASSIGNMENTS, TO OIL WELL SUPPLY COMPANY, OF PITTSBURGH, PENNSYLVANIA, A CORPORATION OF NEW JERSEY

TRAVELING BLOCK

Application filed February 13, 1929. Serial No. 339,625.

This invention relates to a new and improved traveling block especially designed for use in connection with the drilling and operation of oil wells.

5 The prime object of the present invention is to provide a block of the character described embodying simple and efficient guard means disposed adjacent the sheaves of the block to prevent accidents due to accidental contact 19 with the ropes mounted on the sheaves.

Further objects of my invention are, to provide a construction enabling the ropes to be strung on the sheaves without removal of the 15 guard and at the same time provide efficient 15 guard means; to provide a construction embodying guard means of a character that will not enlarge the block structure nor render it difficult to handle; and a construction including 20 guards embodied in a unitary frame 20 structure.

In the accompanying drawings, which illustrate applications of my invention:

Fig. 1 is a side elevational view of a traveling block embodying my invention;

25 Fig. 2, a side elevational view;

Fig. 3, a detail sectional view taken on the line III—III of Fig. 1, and particularly showing a portion of the guard and a portion of a division plate of the block;

30 Fig. 4, a detail view showing a modification; in this instance, a portion of the guard is formed integral with a division plate; and

Fig. 5, a detail sectional view taken on line V—V of Fig. 4.

35 Referring to the drawings, 5—5 designates the side plates or members of the traveling block frame; these plates being connected near their centers by a transversely extending sheave shaft 6 having nuts 7 mounted on the 40 ends of said shaft. The side plates of the frame are further joined together near their tops and bottoms by means of tie bolts or members 8 and 9 respectively.

10 designates a plurality of sheaves mounted 45 on the shaft 6 in the usual manner, and 11 designates a series of partition or separator plates mounted like the side plates and disposed therebetween. Said plates 11 are maintained in spaced relation by means of 50 spreader elements 12 carried on the respective

tie rods and particularly shown on the top tie rod 8 in Fig. 2. These plates or diaphragms, as well as the side plates 5—5, are preferably of a configuration to permit a slight extension of the rims of the sheaves beyond the plates, as particularly shown by Fig. 1. This construction permits the block to be handled readily, as it may be moved along on the derrick floor and other places by means of the projecting portions of the sheaves.

The frame of the traveling block has a flat base portion enabling the frame or the block body to be supported in an upright position after the clevis carrier and clevis structure are swung free of the lower ends of the side members 5—5.

Pivottally connected to the upper tie bolt 8 is a block supporting member 13 designed to be connected with a rope or cable, not shown. Suspended within the frame and near its base portion and on the lower tie bolt is a clevis carrier structure 14. This carrier, as above stated, is adapted to be swung on the lower tie bolt 9 in such manner that it will be free of the base portion of the block, thereby permitting the block to stand in an upright position when it is desired to string the line or for other purposes. 15 designates a clevis carried by the clevis carrier.

An important and characteristic feature 35 of the present invention resides in the guard means for protecting the sheaves and the ropes thereon from accidental contact with the hands of operators from parts or members of the rig or other articles falling onto 40 the block and becoming entangled with the ropes.

These means, as illustrated and as preferred, are embodied in and really constitute 45 a part of the block structure, and are to be distinguished from the usual detachable guard devices heretofore employed with blocks of the character of my invention. The guards, as shown, are either fixedly secured to the side members and/or the separator plates, as in the form of Fig. 1, or partly 50 comprise integral portions of the separator plates, as in the form of Fig. 4.

The guards are disposed adjacent the ropes and sheaves on opposite faces of the frame,

and include a plurality of members or elements 15 and 16 spaced from each other as shown to enable the stringing of the block without removal of or interference by said guard elements.

Elements 15 and 16 each comprise a web portion 18 and a head or flange portion 19, the head portion 19 of the outwardly disposed elements 15 projecting from one side 5 of the web portion only, while the flanged portions 19 of the elements 16 project from both sides of the webs of said elements. These elements are designed to be respectively fixedly secured to the upper outer edges of 10 the side plates 5-5 and the separator plates 11, as by welding the webs thereto, as shown at *a* in Figs. 1 and 3, although they may be permanently secured to the side edges by other means.

20 The head portions or the flanges of the guard elements are preferably secured to the web portions by welding, as indicated at *b*, although if desired these guard elements may be made as an integral element. The 25 web portion 18 of the respective guard elements of the form of Fig. 1 comprises an angular sheet metal plate having an inner edge shaped to conform to the edge of a side and/or a division plate to which it is welded. 30 This provides, after the head 19 is secured, an upwardly and then an inwardly-extending element (see Fig. 1) with the head thereof extending over a portion of a sheave or portions of adjacent sheaves mounted in the block frame. By the employment of a plurality 35 of these elements disposed in spaced-apart relationship to provide openings therebetween and fixedly secured to the block, I provide efficient guard means functioning in the 40 manner above described.

In the form of Fig. 4, the separator or division plates 11*a* are formed with angular projecting portions 20, said portions entering 45 into the formation of the guard element construction. In this form, the heads 19*a* are welded to the portions 20. It will be understood that the guards of the form of Fig. 4 will function similarly to the guards of Fig. 1 and that when the block structure is assembled, very little difference in construction 50 between the two forms is apparent. In the form of Fig. 4, the plates 11*a* are shaped relatively to the sheaves, indicated at 10*a*, to provide a slight projection of the sheaves 55 from the block frame.

I claim:

1. In a traveling block, a frame including a plurality of sheave separator plates, a plurality of sheaves carried in the frame, and individual fixed guards for the sheaves permanently secured to the separator plates and disposed on opposite faces of the frame, the adjacent guards being spaced to permit the stringing of the sheaves.

2. In a traveling block, a frame including

side plates and a plurality of sheave separator plates, a plurality of sheaves carried in the frame, and individual fixed guards for the sheaves permanently secured to the side plates and the separator plates and disposed on opposite faces of the frame, the adjacent fixed guards having openings between them to permit the stringing of the block without removal of the guards.

3. In a traveling block, a frame including a plurality of sheave separator plates, a plurality of sheaves carried in the frame, and individual fixed guards for the sheaves permanently secured to the separator plates and disposed on opposite faces of the frame, said guards each including spaced apart guard elements welded to the separator plates.

4. In a traveling block, a frame including a plurality of sheave separator plates, a plurality of sheaves carried in the frame, and a fixed guard for the sheaves comprising individual guard members one carried by each separator plate.

5. In a traveling block, a frame including a plurality of sheave separator plates, a plurality of sheaves carried in the frame having their rims extending beyond the frame, and a fixed guard for the sheaves comprising individual guard members extending one from each separator plate above the extending rims of the sheaves.

6. In a traveling block, a frame including side plates and a plurality of sheave separator plates, a plurality of sheaves carried in the frame, and fixed guards for the sheaves disposed on opposite faces of the frame, each including a plurality of laterally spaced apart individual guard elements respectively secured to the side plates and the separator plates.

7. In a traveling block, a frame having plates, sheaves disposed and journaled between the plates and extending laterally beyond the sides thereof, said plates having side edge portions extending upwardly and inwardly from approximately a plane passing horizontally through the axis of the sheaves, and individual guards secured to said portions and arranged to permit stringing of the sheaves at all times.

8. In a traveling block, a frame having plates, sheaves disposed and journaled between the plates and extending laterally beyond the sides thereof, said plates having side edge portions extending upwardly and inwardly from approximately a plane passing horizontally through the axis of the sheaves, individual guards relatively close to the sheaves, said guards having webs secured to and forming extensions of said edge portions, and laterally extending heads on said webs.

9. In a traveling block, a frame having plates, sheaves disposed and journaled between the plates and extending laterally be-

yond the sides thereof, said plates having side edge portions extending upwardly and inwardly from approximately a plane passing horizontally through the axis of the sheaves, individual guards relatively close to the sheaves, said guards having webs in the planes of the plates and welded to the latter at said portions, and heads of angular form extending laterally from the outer edges of the webs and over the sheaves.

10 In testimony whereof I affix my signature.
EDGAR E. GREVE.
